UNITED STATES PATENT OFFICE.

JOHN F. McCANNA, OF CHICAGO, ILLINOIS, ASSIGNOR TO THE JOHN F. McCANNA COMPANY,
OF CHICAGO, ILLINOIS, A CORPORATION OF ILLINOIS.

AUTOMOBILE LUBRICATING-PUMP.

No. 861,755.

Specification of Letters Patent.

Patented July 30, 1907.

Application filed July 25, 1904. Serial No. 217,942.

To all whom it may concern:

Be it known that I, JOHN F. McCANNA, a citizen of the United States, residing at Chicago, in the county of Cook and State of Illinois, have invented certain new and useful Improvements in Automobile Lubricating-Pumps, of which the following is a specification.

This invention relates to certain new and useful improvements in Lubricating pumps designed to feed a suitable lubricant in uniform quantities to moving parts of machinery, such as the driving mechanism of automobiles and the like.

The invention consists of the combination and arrangement of parts hereinafter particularly described and designated in the appended claims.

In the drawings, Figure 1 is a perspective view of my invention showing the same as arranged for a series of six pumps and having the oil tank partially broken away to illustrate the driving mechanism of one of the pumps; Fig. 2 is a view in elevation showing the pumps and the top or cover by which they are supported removed from the oil tank; and Fig. 3 is a vertical transverse section, partially in elevation and on an enlarged scale, showing one of the pumps, the tank or reservoir being mounted on the dash board of an automobile or other suitable support.

The oil tank or reservoir 10 designed to contain the lubricant and in which the pumps are located may be of any suitable shape and of a size depending on the number of pumps employed. In the present instance the tank is of rectangular shape, and is shown as arranged for a series of six pumps. The tank 10 is provided with a cover or cap plate 11 which may be secured in place by any suitable means as by screws 12. The pumps are supported by the cover 11 and are so constructed and arranged that when the cover is removed the pumps together with their associated parts, are disconnected from the common driving means and withdrawn from the tank. While I have shown a series of six pumps it is to be understood that this showing is merely arbitrary, and that only one may be employed or any other number desired, the only changes necessary being in the size of the tank and the length of the cam shaft for reciprocating the pistons of the pumps and hereinafter to be referred to.

The pumps are constructed as clearly shown in Figs. 1 and 3 and as they are the same in all particulars a description of one will suffice for all. The pump barrel 13 of each pump is arranged horizontally and is provided with a vertical depending extension or tube 14 which preferably extends to nearly the bottom of the tank 10 so as to be supplied with oil until the tank is practically empty. This tube 14 may be integral

with the barrel 13, but is shown as threaded at the upper end to engage a threaded socket 15 depending from the pump barrel. Located in the socket 15 and adapted to seat upon the upper end of the tube 14, so as to normally close the outlet of the said tube, is a gravity valve 16 which is prevented from rising out of the socket by a web 17 at the upper end of the socket, which web is provided with apertures to permit of the passage of oil into the pump barrel. Also leading from the barrel 13 is an upwardly extending tube or conduit 18 which is threaded at its lower end to screw into an internally threaded socket 19 extending vertically from the end of the barrel 13, a passage 20 of lesser diameter than that of the socket 19 leading from the barrel into the said socket. In the chamber of the socket is located a gravity valve 21 normally closing the passage 20 and which is prevented from rising into the tube 18 by the lower end of the latter. The tube 18 is connected to the cover 11 in any suitable manner. As shown it passes through an aperture in the cover and is threaded at its projecting end to receive a nut 22 between which and a collar 23 the tube 18 may be securely clamped to the cover. The pump piston 24 is fixed at its outer end to a yoke or inverted substantially U-shaped element 25 which is arranged transversely of the tank and between the arms of which extends a horizontal shaft 26 journaled in the ends of the tank. This shaft is provided with an eccentric 27 which cooperates with the arms of the yoke to reciprocate the piston.

In order to maintain the yoke in its vertical position a guide rod 28 is fixed to the socket 15 and is extended rearwardly through an aperture in the lower end of the adjacent arm of the yoke. This guide rod prevents oscillation of the yoke and maintains the same in proper alignment with its associated eccentric.

Any suitable means may be employed to rotate the eccentric shaft 26, but preferably and in order that the supply of oil fed to the bearings may be made dependent on the movement of the parts being lubricated, I employ a connection for transmitting motion from the driving mechanism of the machine designed to be lubricated. To this end the shaft 26 has fixed thereon a worm gear 29 which meshes with and is driven by a worm shaft 30. This worm shaft is disposed horizontally and is journaled at its front end in a bearing 31 on the front wall of the reservoir, while its other end is journaled in a sleeve 32 set into the rear wall of the tank, this sleeve being secured in place by means of bolts 33 passing through the wall of the tank and lugs 34 formed on the sleeve, nuts 35 being provided to securely clamp the sleeve in place. Suitable packing is provided for

the apertures in the wall of the tank through which the bearing sleeve and securing screws pass and the outer end of the sleeve is provided with a packing gland 36 which is held in position by nuts 37 threading on the 5 ends of the bolts 33 which also extend through lugs 38 projecting from the said gland. In order to prevent longitudinal movement of the worm shaft 30 the latter is provided with a shoulder 40 which abuts against the inner end of the bearing sleeve 32 and is formed by 10 reducing the end of the shaft passing through the said sleeve. The rear end of the worm shaft 30 extends beyond the rear wall of the tank and is provided with a suitable means, such as the belt wheel 39 to which motion is communicated from the driving mechanism being 15 lubricated. Suitable packing such as 40⁴ is provided for the pump barrel to prevent oil leaking back past the piston into the tank.

Means are provided for varying the stroke of the pump piston in order to vary the rate of feed of the 20 pump. To this end one of the arms of the yoke 25, in the present instance that adjacent to the front wall of the tank and indicated by the numeral 41, is inclined or beveled on its inner face and coacts with a sliding block or wedge 42, the face of which adjacent the arm 25 41 is inclined or beveled reversely thereto. The block 42 is adapted to slide on the arm 41 and in order to prevent disengagement therefrom it is provided with a fin 43 which fits in a guide way, shown in dotted lines in Fig. 3, on the adjacent face of the arm 41. The block 30 42 is supported by a stem or rod 44 which passes through the arm 41 and the upper end of which passes through an aperture in the cover 11 and is threaded to receive an adjusting nut 45, the said aperture being of greater diameter than the stem so that the latter may rock or 35 oscillate freely as the piston 24 is reciprocated. The stem 44 is pivotally connected to the wedge block 42, as shown in dotted lines in Fig. 3, in order to accommodate the block to this rocking movement of the stem. The nut 45 is provided with a recess on its under face 40 to receive a pin 46 fixed to the cover 11 to hold the nut against accidental rotation, while the latter is readily disengaged from the pin when it is desired to adjust the block by lifting the nut slightly. With the wedge block 42 in the position shown in Fig. 3, that is to say 45 in its elevated position, the eccentric turns freely between the block 42 and the opposite arm of the yoke but all lost play is eliminated and the piston is given its full stroke. To shorten the stroke of the piston the nut 45 is turned so as to lower the block, which owing 50 to the inclined faces of the block and arm 41 provides lost motion between the yoke and eccentric, which lost motion may be varied at will. By lowering the block far enough the pump may be thrown entirely out of action.

55 The oil is discharged by the pump through a tube 47 which is in threaded engagement with the upper end of the tube 18 and this tube leads to a feed pipe 48 which conveys the oil to the bearing to be lubricated. This tube 47 is provided with a bleeder-test by a lateral 60 branch tube 49 which discharges downwardly through a sight feed glass 50 opening at its lower end through the top of the lid, and the passage through the branch tube is opened and closed by a screw valve 51. The upper end of the tube 47 has its bore enlarged to pro-

vide a seat for a gravity valve 52 normally closing the 65 passage through the said tube.

The tank may be supported in any suitable manner. When employed with an automobile it is preferably carried by the dash board thereof, as shown in Fig. 3, and is located in such position as to be within convenient reach of the chauffeur or driver. When so employed the dash board as 53, is provided with an opening 54, through which the end of the worm shaft 30 passes, and also with an opening 55 through which each of the feed pipes 48 passes. In order to permit of the removal of the cover of the tank the tubes 47 are arranged to be readily disconnected from the feed pipes. To this end each tube 47 has its upper end screw threaded and the interior of its upper end is of a hollow cone shape, to coöperate with the conical end of a joint 56 by which the tube 47 is joined to an elbow 57 on the inner face of the dash board and into which the feed pipe 47 is screwed. A nut 58 serves to hold the joint and tube 47 securely together but permits these parts to be readily separated. The openings 55, through 85 which the feed pipes 48 extend, are elongated vertically for a purpose to be hereinafter explained.

It is to be understood that when a plurality of pumps is employed each pump is constructed and mounted in the manner heretofore described and is entirely separate from and independent of the other or others, except that the eccentric shaft is common to all the pumps and passes through the piston yoke of each pump as shown in Fig. 3. The tank is provided with a filling strainer 59 carried by the cover and closed by a 95 plug 60 in the usual manner; and it also has a gage glass 61 opening at its bottom into the tank, for indicating the quantity of oil in the tank.

In operation, a slow reciprocating movement is imparted to the piston of each pump, the speed depending 100 on the speed of the part from which motion is derived. As the piston moves on its out or suction stroke oil is sucked up through the tube 14, past the valve 16, and enters the pump barrel. Upon the discharge or in stroke of the piston the valve 16 is pressed to its seat and, 105 the valve 21 raised so that the oil is forced through the tube 18 and past the valves 21 and 52 and out of the feed pipe 48 to the bearing, the feed pipe being normally full owing to the valve 21 which, upon the suction or outstroke of the piston, falls back to its seat and prevents the oil in the feed pipe from flowing back into the pump barrel.

When it is desired to ascertain the rate of feed, the bleeder valve 51 is opened and the valve 52 being held to its seat by the pressure of oil in the feed pipe, the oil forced out by the pump passes into the branch pipe 49 and drops back into the tank through the glass 50 which is so located as to be readily observable by the attendant. This sight feed is particularly useful for indicating when the desired rate of feed has been secured by 110 the adjustment of the wedge block of the pump.

All of the operative parts of the pumps proper being carried by the cover and the yokes being so constructed as to readily slip vertically off the eccentric shaft, the pumps, yokes and adjusting devices may be removed 115 from the tank by simply unscrewing the lid, uncoupling the connections 56 and sliding the elbows 57 upwardly, this being permitted by the elongated slots 55

through which the feed pipes pass, and then merely lifting the cover upwardly off the tank. This avoids the necessity of detaching the pumps separately and of disassembling the mechanism of the pumps themselves when it is necessary to make repairs or when for other reasons it is desired to attain access to the interior of the tank and greatly facilitates the assembling and disassembling of the mechanism.

Each pump is capable of being adjusted independently of the others, and the means for attaining the adjustment are located outside of the tank so as to be accessible at all times. The operating parts including the pump and the mechanism for operating the pistons are all located in the tank and submerged in the oil, thereby keeping them entirely free from dust and dirt and insuring thorough lubrication of the parts.

What I claim as new and desire to secure by Letters Patent of the United States, is:

1. In a lubricator, the combination with a reservoir, of a pump removably mounted in the reservoir and having a reciprocating piston, actuating means located in the reservoir, and means carried by the piston and co-operating with the actuating means and being disengaged therefrom by and upon the removal of the pump.

2. In a lubricator, the combination with an oil reservoir, and piston actuating means located in the reservoir, of a removable plate for the reservoir, pump carried by the plate and extending into the reservoir and having a reciprocating piston, and means carried by the piston and co-operating with the piston-actuating means to drive the piston and being disengaged therefrom by and upon the removal of the plate.

3. In a lubricator, the combination with an oil reservoir, and an eccentric located therein, of a removable cap plate for the reservoir, a pump carried by the cap plate and extending into the reservoir and having an inlet and an outlet, and a yoke connected with the pump piston and co-operating with the eccentric and being disengaged therefrom by and upon the removal of the cap plate.

4. In a lubricator, the combination with an oil reservoir, an eccentric located therein, and means for driving the eccentric, of a removable cap plate for the reservoir, a series of pumps carried by the cap plate and depending into the reservoir, each of the said pumps having an inlet and an outlet, and an inverted substantially U shaped yoke connected with each pump piston and co-operating with the eccentric and being disengaged from the eccentric by and upon the removal of the cap plate.

5. In a lubricator, the combination with an oil reservoir, an eccentric located therein, and means for driving the eccentric, of a removable cap plate for the reservoir, a series of pumps carried by the cap plate and depending into the reservoir, each of the said pumps having an inlet and an outlet, and an inverted substantially U shaped yoke connected with each pump piston and co-operating with the eccentric and being disengaged therefrom by and upon the removal of the cap plate.

6. In a lubricator, the combination with an oil reservoir, an eccentric shaft located therein, and means for driving the shaft, of a removable cap plate for the reservoir, a pump carried by the cap plate and having an inlet in the reservoir and an outlet extending through the cap plate, a support for the reservoir having an elongated opening, a feed pipe passing through the opening, a coupling detachably connecting the outlet and the feed pipe, and a yoke fixed to the pump piston and co-operating with the eccentric shaft and being disengaged therefrom by and upon the removal of the cap plate.

7. In a lubricator, the combination with an oil reservoir, an eccentric therein, and means for driving the eccentric, of a removable cap plate for the reservoir, a series of pumps secured to and carried by the cap plate and each of which is provided with an oil inlet in the reservoir and an outlet extending through the cap plate, a feed pipe in extension of the outlet, a support having a vertical slot through which the feed pipe passes, a coupling detachably

connecting the feed pipe and the outlet, and an inverted substantially U shaped yoke connected with the piston of each pump and co-operating with the eccentric and which is adapted to be disengaged therefrom by and upon the removal of the cap plate.

8. In a lubricator, the combination with a reservoir, of a pump, means for reciprocating the pump piston, and a slide movable with the plunger and co-operating with the said means for varying the amount of movement of the piston.

9. In a lubricator, the combination with a reservoir, of a pump therein having a reciprocating piston, an eccentric for reciprocating the piston, and an adjustable wedge movable with the piston and co-operating with the eccentric for varying the amount of movement of the piston.

10. In a lubricator, the combination with an oil reservoir, of an eccentric, a pump in connection with the reservoir, a yoke on the pump piston and co-operating with the eccentric, and a sliding member carried by the yoke for varying the amount of movement given to the piston by the eccentric.

11. In a lubricator, the combination with an oil reservoir, of an actuating eccentric, a pump in connection with the reservoir, a yoke on the pump piston and co-operating with the eccentric, a slide block co-operating with one of the arms of the yoke, and means for moving the block to vary the amount of movement of the piston.

12. In a lubricator, the combination with an oil reservoir, of an actuating eccentric, a pump in connection with the reservoir, a yoke on the pump piston co-operating with the eccentric and one of the arms of which is inclined on its inner face, a block having an inclined face co-operating with the said arm, and means for moving the block to vary the amount of movement of the piston.

13. In a lubricator, the combination with an oil reservoir, of an actuating eccentric, a pump in connection with the reservoir, a yoke on the pump piston co-operating with the eccentric and having one of its arms inclined on the inner face, a sliding block having an inclined face co-operating with the inclined face of the said arm, a stem pivoted to the block, and means for moving the stem.

14. In a lubricator, the combination with an oil reservoir having a cover, of an actuating eccentric shaft, a pump in connection with the reservoir, a yoke on the pump piston and co-operating with the eccentric and having one of its arms inclined on its inner face, a sliding block inclined reversely to and co-operating with the inclined face of the said arm, a stem pivoted to the block and threaded at its free end, the cover having an enlarged aperture through which the stem passes, and an adjusting nut on the threaded stem.

15. In a lubricator, the combination with an oil reservoir having a cover, of an eccentric shaft located in the reservoir, a series of pumps carried by the cover and depending into the reservoir, a yoke on the piston of each pump and co-operating with the eccentric shaft, a wedge block co-operating with one of the arms of the yoke, a stem pivoted to the wedge block and threaded at its upper end, the cover having an enlarged aperture through which the stem passes, and an adjusting nut on the threaded stem.

16. In a lubricator, the combination with an oil reservoir having a cover, of an eccentric shaft located in the reservoir, a series of pumps carried by the cover and depending into the reservoir, an inverted substantially U shaped yoke co-operating with the eccentric shaft to reciprocate the pump pistons, a guide rod fixed to the pump and on which the yoke reciprocates, a wedge block co-operating with one of the arms of the yoke, a stem pivoted to the block and threaded at its upper end, the cover having an enlarged aperture through which the stem passes, and a nut on the stem to adjust the block to vary the movement of the piston.

17. In combination in a force feed lubricator, a reservoir, a pump depending into the same, means within the reservoir for operating the pump, a device for adjusting the stroke of the pump, said pump with its adjusting device being detachable from said operating means and also removable through the top of the reservoir by a straight vertical movement of said parts as a whole.

18. In combination in a force feed lubricator, driving means, a reservoir, a pump depending into the same and consisting of a movable part having connections extending to one side of the vertical plane thereof for connection with the driving means, said driving means being also located within the reservoir and from which the pump is disengaged by a straight vertical movement of said pump.
19. In combination in a force feed lubricator, a reservoir, a drive shaft therein, a pump extending into the reservoir on one side of the shaft and having a laterally ex-

tending connection with said shaft adapted to be engaged and disengaged therefrom by a straight vertical movement of the pump in relation to the shaft.

In testimony whereof I affix my signature in presence of two witnesses.

JOHN F. McCANNA.
